CLAIM

The ornamental design for a servo amplifier, as shown and described.

DESCRIPTION

FIG. 1 is a front-right side-top perspective view of a servo amplifier showing my new design;

FIG. 2 is a front-left side-top perspective view thereof;

FIG. 3 is a front-right side-bottom perspective view thereof;

FIG. 4 is a front-left side-bottom perspective view thereof;

FIG. 5 is a front view thereof;

FIG. 6 is a rear view thereof;

FIG. 7 is a top plan view thereof;

FIG. 8 is a bottom plan view thereof;

FIG. 9 is a right side view thereof; and,

FIG. 10 is a left side view thereof.

The broken line showing of the remainder of the servo amplifier represents portions which form no part of the claimed design.
